United States Patent Office.

WILLIAM BRADY AND CHRIST. H. BRADY, OF MOUNT JOY, PENNSYLVANIA, ASSIGNEES TO THEMSELVES AND H. A. BRADY, OF SAME PLACE.

Letters Patent No. 92,255, dated July 6, 1869.

IMPROVEMENT IN LIFTING-JACKS.

The Schedule referred to in these Letters Patent and making part of the same.

To all whom it may concern:

Be it known that we, WILLIAM BRADY and CHRIST. H. BRADY, of Mount Joy, in the county of Lancaster, and State of Pennsylvania, have invented certain new and useful Improvements in Stove-Lifter; and do hereby declare that the following is a full, clear, and exact description thereof, reference being had to the accompanying drawings, and to the letters of reference marked thereon.

The nature of our invention consists in the construction and arrangement of a device for lifting stoves.

In order to enable others skilled in the art to which our invention appertains to make and use the same, we will now proceed to describe its construction and operation, referring to the annexed drawings, which form a part of this specification, and in which—

Figure 1 is a side elevation of the machine;

Figure 2 is a perspective of a handle, which may be substituted in place of the one shown in fig. 1; and

Figure 3 is a plan view of the lifting-rack and movable jaws.

A represents a bed-plate or bar of suitable length, which, at its rear end, is bent upward, and then forward, in the shape shown in fig. 1, so as to be nearly on a line with the lower front end.

It is then bent upwards, forming a perpendicular standard, B.

It will be seen that the flat or straight portion of the bar A forms the bed-piece of the whole machine, and is cast in one piece with the standard B, which latter is provided with a slot of suitable length.

In this slot is inserted a block, C, projecting from the rear side of a bar, D, and which bar is held in front of the standard B by means of a pin, a, which passes through the block C, in rear of said standard.

The bar D, which is perpendicular, can thus be raised or lowered at will, as the block C slides up and down in the slot of the standard B.

The bar D is provided on its front side with a series of teeth, b, and on each side, at the base of said teeth, with a flange, c, which flange, at the lower end of the bar, extends to the rear side of the same.

On the bar D, the jaws E E are placed, each of said jaws being grooved near its rear end, to allow the flange c to pass through the same, and extending a suitable distance in front of the bar.

The jaws E E are riveted, or otherwise secured together, and on their under side provided with a projection, d, which catches on the teeth b.

The clamp, thus formed of the two jaws E E, can be placed at any point desired on the bar D, and held

there by its own weight, which forces the projection d into or on any one of the teeth desired.

This clamp may be cast in one piece, if so desired, and this I prefer to do.

In rear of the slotted standard B, and on the upper portion of the bar A, are placed two ears, e, between which a lever, F, is pivoted, the front end of said lever extending under the block C, and the rear end extending a suitable distance, and forming a handle for operating the machine.

By raising the lower end of the lever F, it will be seen the bar D and block C are allowed to slide down as far as the slot in the standard B will allow.

By then setting the clamp or jaws E under the stove, and bearing down on the lever F, the stove will be raised up; and when thus raised up, it may be held as long as desired by a loop, h, pivoted or hinged at a suitable point on the bar A, which loop is hooked to a hook, m, on the under side of the lever, thus preventing the lever from raising up.

Instead of using the lever F for raising the toothed bar, we may use an auger-shaped cam, G, provided with a handle, H, represented in fig. 2.

The bar A, being provided with a pin at a suitable distance from the slotted standard B, and the cam G having a hole through its centre, the cam is placed around said pin so that the auger-flange of the cam projects under the block C. By now turning the handle H, the block and lifter will be raised by the auger-flange of said cam G.

Having thus fully described our invention—

What we claim as new, and desire to secure by Letters Patent, is—

1. The bed-piece A, constructed substantially in the bent form herein described, and provided with a perpendicular slotted standard, B, as shown and described.

2. In combination with the bed-piece A and slotted standard B, the toothed and flanged bar D, block C, and clamp or jaw E, all constructed and arranged to operate substantially as and for the purposes herein set forth.

3. The arrangement of the ears ee on the bed-piece A, the lever F, loop h, and hook m, or their equivalents, all substantially as and for the purposes herein set forth.

In testimony that we claim the foregoing, we have hereunto set our hands, this 27th day of February, 1869.

WILLIAM BRADY.
CHRIST. H. BRADY.
